ELECTRIC IRON

William L. Gould, Albany, N. Y.

Application April 15, 1944, Serial No. 531,250

6 Claims. (Cl. 219—25)

1

This invention relates to electric irons of that type embodying a plurality of sections which may be used together or separately to provide irons of different weights and sizes.

The primary object of the present invention is to provide an electric iron of the above kind in which each iron section has a permanent handle member, an electrical heating element and a plug for reception of the socket of an attachment cord whereby the heating element may be connected with a source of electricity, each iron section having an ironing surface, mechanical means being provided to rigidly connect the iron sections together to form a continuous ironing surface, and means including the attachment plug of one section and an electrical connector socket carried by the other iron section being provided to interconnect the heating elements of the sections when they are mechanically secured together.

Another object of the present invention is to provide an electric iron of the above kind wherein each iron section has a handle member, an electrical heating element, and an attachment plug for reception of the socket of an attachment cord whereby the electrical heating element of each iron section may be connected with a source of electricity, mechanical means being provided to connect the iron sections together, and the handle members of the sections being constructed and arranged to coact when the iron sections are assembled to form a most satisfactory handle for the heavier iron presented by the assembled iron sections.

With the above objects in view, and others that will become apparent as the nature of the invention is better understood, the present invention consists in the novel form, combination and arrangement of parts hereinafter more fully described, shown in the accompanying drawings and claimed.

In the drawings, wherein like reference characters indicate corresponding parts throughout the several views:

Figure 1 is a side elevational view of an electric iron constructed in accordance with the present invention.

Figure 2 is a front elevational view thereof.

Figure 3 is a bottom plan view of the same.

Figure 4 is an enlarged fragmentary longitudinal section taken on the plane of line 4—4 of Figure 3.

Figure 5 is a developed bottom plan view showing the sections of the iron of Figure 1 separated.

Figure 6 is an enlarged transverse section taken on line 6—6 of Figure 1.

2

Figure 7 is a top plan view of a modified form of the invention.

Figure 8 is an enlarged transverse section taken on the line 8—8 of Figure 7.

Figure 9 is a side elevational view, partly broken away and in section, of the iron shown in Figure 7.

Figure 10 is a bottom plan view, partly broken away and in section, of a further modification of the present invention.

- 10 Referring in detail to the drawings, and particularly to the embodiment of the invention shown in Figures 1 to 6, inclusive, the iron includes two sections 5 and 5a, each having an ironing surface 6 and 6a and provided with a permanent handle member 7 and 7a. Also, in this embodiment, each iron section has a pointed front end 8 and 8a. The upper surface of the pointed forward end of each section is preferably rounded and inclined to the ironing surface. Accordingly, 15 the front section 5 is provided in its rear end and under side with a cavity or recess 9 to receive the forward end of the rear section 5a and to so locate the sections with respect to each other, when said sections are joined together, that the surfaces 6 and 6a will present a continuous ironing surface. Any suitable means may be provided to mechanically connect the sections together, such as aligned ears 10 and 11 on opposite sides of the iron sections, which ears are adapted to receive 20 bolts 12 having nuts 13 threaded thereon to tightly draw the iron sections together. The handle members 7 and 7a are preferably so formed and arranged that they will align with each other at their adjacent ends and coact to form a most 25 desirable large handle for the heavy iron presented when the iron sections are joined together. However, it will be apparent that when the iron sections are separated, each of them will have a permanent handle member so that either one may 30 be independently used with respect to the other. In order to make this completely possible, each iron section is provided at the rear thereof with an attachment plug 14 or 14a adapted to receive the socket of an attachment cord, each iron section having its own independent heating element. As shown in Figure 6, the section 5 has a heating element 15 electrically connected to the plug 14, 35 while the section 5a has a heating element 15a electrically connected to the plug 14a.
- 40 Provided at the front of the rear iron section 5a is an electrical socket 16 adapted to receive the contact pins of the plug 14 of the front section 5a when the iron sections are mechanically joined together, the contacts of the socket 16 being connected to the plug 14a of the iron sec- 45 50 55

tion 5a. Thus, when the iron sections are joined together, their heating elements are automatically electrically connected together in parallel by connecting the corresponding terminals of plugs 14 and 14a in series so that both ironing surfaces 6 and 6a will be heated. In this event, the socket of the attachment cord will of course be applied to the exposed plug 14a of the rear iron section 5a.

In the embodiment of Figures 7 to 9, inclusive, the iron is composed of a main larger lower iron section 5' and an upper smaller iron section 5a' adapted to be centrally disposed upon the section 5' and mechanically secured thereon by means of screws 12' passing through marginal recessed portions of the upper section 5a' and threaded into the lower section 5'. When the sections are used together, only the ironing surface 6' of the lower section 5' is used. However, the upper section 5a' has a bottom ironing surface 6a' which is used when the upper iron section is employed by itself upon being detached from the lower section 5'. The sections 5' and 5a' respectively have heating elements 15' and 15a', the former being connected with an attachment plug 14' and the latter being connected with an attachment plug 14a'. The plugs 14' and 14a' are respectively located at the rear ends of the sections 5' and 5a', as shown in Figure 7.

Section 5' has a handle member 7', while section 5a' has a handle member 7a'. These handle members are used and they coact the same as the handle sections 7 and 7a of the iron shown in Figure 1, except that the smaller upper iron section 5a' has an opening 17 therethrough upwardly through which the handle member 7' of the iron section 5' projects. This permits the handle member 7' to pass downwardly through the opening 17 when the iron sections are separated. In other words, it permits separation of the iron sections even though each has its own permanent handle member. Obviously, either iron section may be used alone, or they may be used in assembled relation, depending upon the size and weight of iron which it is desired to use.

In the embodiment of Figure 10, the iron sections 5b and 5c are mechanically joined in end-to-end relation by means of bolts 12b passing through lugs 10b and 11b on the adjacent flat rear ends of the sections, a nut 13b being threaded on each bolt so that the sections may be tightly drawn and secured together. A main distinction between this form of the invention and that shown in Figure 1 is that the iron sections point away from each other instead of in the same direction. The iron section 5b has a handle member 7b, and the iron section 5c has a handle member 7c respectively corresponding to the handle members 7 and 7a of Figure 1. Also, each iron section 5b and 5c has its own electrical heating element and is provided with a flat bottom ironing surface 6b and 6c. The surfaces 6b and 6c form a continuous ironing surface when the sections 5b and 5c are secured together. In this embodiment, the flat rear ends of the sections have electric sockets 16b and 16c, while a double connector plug 18 is provided to simultaneously engage both of the sockets 16b and 16c for electrically connecting the heating elements of the two iron sections in parallel with each other as in the form of Figures 1 to 6, inclusive when said iron sections are joined together. Either iron section may have an additional plug corresponding to plug 14a. The

connector plug 18 may be left in either the socket 16b or the socket 16c when the iron sections are separated, whereby either desired iron section may be employed by itself. For instance, if the connector plug 18 is left engaged in the socket 16b of the iron section 5b, one set of contact pins of the connector plug 18 will project from said section 5b for reception in the socket of an attachment cord. In a like manner, if the connector plug 18 is left engaged in the socket 16c of the section 5c, a set of contact pins of the connector plug 18 will project from said section 5c for reception in the socket of the attachment cord. It will thus be apparent that either iron section may be employed alone and connected with a source of electricity for heating its ironing surface. Any suitable means may be provided for releasably securing the connector plug 18 to the particular iron section in which it is allowed to remain engaged. Obviously, when the iron sections are separated, each will have its own handle member.

An advantage of the construction shown in Figures 7 to 9, inclusive, is that it presents an unbroken ironing surface when the iron sections are joined together. However, this is not a serious objection with the other forms of the invention if they are accurately aligned and carefully constructed so that the ironing surfaces of the iron sections will be exactly flush when the iron sections are secured together. This requires some precision in manufacture so as to afford no shoulder or break at the joint between the sections of the iron.

From the foregoing description, it is believed that the construction and operation, as well as the advantages of the present invention, will be readily apparent to those skilled in the art. The invention is susceptible of other modifications and changes in details of construction such as fairly fall within the spirit and scope of the invention as claimed.

What I claim is:

1. An electric iron comprising a plurality of at least two iron sections, each having a pointed front end and an ironing surface and each provided with a separate permanent handle member, a heating element for each iron section, means at one end of each iron section to facilitate electrical connection of its heating element with a source of electricity, and mechanical means for rigidly securing said iron sections together.

2. An electric iron comprising a plurality of at least two iron sections, each having a pointed front end and an ironing surface and each provided with a separate permanent handle member, a heating element for each iron section, means at one end of each iron section to facilitate electrical connection of its heating element with a source of electricity, and mechanical means for rigidly securing said iron sections together, the handle members of the sections being so formed and arranged that they will align and coact to form an enlarged handle for the heavier iron provided by the assembled iron sections.

3. An electric iron comprising a plurality of at least two iron sections, each having a pointed front end and an ironing surface and each provided with a separate handle member and an electrical heating element, means to mechanically secure said iron sections together in abutting relation so that their ironing surfaces form a continuous ironing surface, means to facilitate electrical connection of the heating element of one iron section with a source of electricity, and

means to automatically connect the heating elements of the other section to said second-named means when said sections are joined together.

4. An electric iron comprising a plurality of at least two iron sections, each having an ironing surface and an electrical heating element, means to mechanically secure said iron sections together in abutting relation so that their ironing surfaces form a continuous ironing surface, means to facilitate electrical connection of the heating element of one iron section with a source of electricity, and means to automatically connect the heating element of the other section to said second-named means when said sections are joined together, one section having a cavity at its read end, both of said sections having a rounded pointed forward end, the forward end of the other section being adapted to snugly fit in said cavity.

5. An electric iron comprising a plurality of 20 two iron sections each having a flat rear end and a pointed front end, mechanical means to secure the sections together with their flat rear ends in abutting relation, said sections having ironing surfaces adapted to form a continuous ironing surface when the sections are joined together, a separate handle member permanent with each iron section, an electrical connector socket at the rear end of each iron section, and

a double-ended connector plug separable from either iron section and adapted to connect the connector sockets of the iron sections when said iron sections are joined together and to provide 5 means for electrically connecting the heating element of either iron section with a source of electricity when the iron sections are separated.

6. An electric iron comprising a relatively large lower iron section having a pointed front end 10 and an ironing surface and provided with a handle member, an upper smaller iron section superposed upon the first-named iron section and detachably rigidly secured thereon, said smaller iron section having a pointed front end and an 15 ironing surface, a handle member permanently carried by the second iron section, each iron section having an electrical heating element, and an attachment plug on the rear end of each iron section for facilitating connection thereof with a source of electricity, the smaller upper iron section having an opening permitting the passage of the handle member of the lower iron section upwardly therethrough when the iron sections are assembled, said handle members being 20 so formed and arranged that they will align and coact to form an enlarged handle for the heavier iron provided by the assembled iron sections.
